UNITED STATES PATENT OFFICE.

JOHN MCTAMMANY, OF WORCESTER, MASSACHUSETTS.

MECHANICAL MUSICAL INSTRUMENT.

SPECIFICATION forming part of Letters Patent No. 390,385, dated October 2, 1882.

Application filed March 19, 1886. Serial No. 195,821. (No model.)

To all whom it may concern:

Be it known that I, JOHN MCTAMMANY, a citizen of the United States, residing at Worcester, in the county of Worcester and State of Massachusetts, have invented certain new and useful Improvements in Automatic Musical Instruments; and I do hereby declare the following to be a full, clear, and exact description of the invention, such as will enable others skilled in the art to which it appertains to make and use the same.

This invention relates to automatic musical instruments which are operated by pedals; and it consists partly in certain improvements, hereinafter described and claimed, in the mechanism for operating the winding and rewinding rollers of the music-sheet.

It also consists in the combination, with a series of reeds and reed-valves, of a corresponding series of small pneumatic motors, each of which operates by external atmospheric pressure to hold one of the said valves closed until an opening of the music sheet comes over the proper reed-duct.

The invention also consists in the peculiar construction and combination of devices for exhausting and filling said pneumatics by means of the main bellows of the instrument and causing them to raise and lower said valves; also, in divers additional details of construction and combination, hereinafter particularly set forth.

In the accompanying drawings, Figure 1 represents a central vertical section, from front to rear, of an instrument embodying my invention. Fig. 2 represents a similar section of the same on the line just within the outer case, on the side next the fan. Fig. 3 represents a plan view of the greater part of said instrument. Fig. 4 represents an enlarged additional detail view illustrating one of the clutch-sleeves and the proximate parts of the roll-spindle and shaft geared therewith.

In the accompanying drawings, A designates the casing of the instrument; B, the two pedals; C, the main or reservoir bellows connected by suitable passages for exhausting air from the interior of the wind-chest A'; and D, one of the two feeder-bellows arranged side by side in front of it, all three bellows standing upright in the lower part of the case A. To

enable said pedals to operate said bellows and certain other devices to the best advantage, I provide a transverse shaft, E, which has upon it two ratchet-wheels, F, that turn therewith, 55 motion being given to said shaft by means of pawls G. These pawls are attached to levers H, of the first kind, which are mounted loosely on said shaft, the outer ends of said levers being connected to said pedals, respectively, by 60 links I. These pawls, ratchet-wheels, and attached parts are arranged to communicate a step-by-step motion to said shaft as said pedals are alternately operated by the player's feet. Cords J, passing from said pedals, respectively, 65 over pulleys j, effect the expansion of the respective feeder-bellows D for the purpose of exhausting the main or reservoir bellows C. The contraction of said bellows D is caused by a spring, j', in each instance. It has not been 70 deemed necessary to illustrate more than one of said feeder-bellows, their construction and arrangement being well known.

The shaft E carries a loose drum, K, which is connected to said shaft by a coiled spring, 75 L, the inner end of the spring being attached to the shaft and the outer end to the drum. Thus the power continuously stored in the spring by the rotation of the shaft is given out through the drum, the spring serving to make 80 the motion regular and even. A belt, M, passes from this drum to a pulley, n, on a small shaft, N, arranged in the upper part of case A, parallel to shaft E. This shaft N is provided with a gear-wheel, N', which meshes 85 with a pinion, o, on another shaft, O, bearing a gear-wheel, O', and a pulley, O''. This latter gear-wheel meshes with a pinion, p, on a fan-shaft, P, and pulley O'' is connected by an endless cord or chain, q', preferably elastic, to a 90 pulley, q, on a shaft, Q. These four shafts N O P Q are journaled in the sides of a rectangular metallic case or frame, Q', so that they may all be removed together, with their gearing, from the instrument. Shafts N and Q extend 95 through the inner wall of said frame or case, and shaft P extends through both walls, bearing a fan, R, outside of the outer wall, which serves as a fly-wheel. This fan-shaft P is movable endwise and provided with a spring, r, 100 which tends to hold its pinion p in position to engage gear-wheel O'.

S designates the winding-roll, and T the re-winding-roll, of the music sheet, the former being arranged in axial alignment with shaft N and the latter with shaft Q, each roll being 5 provided with spindle N² or Q² for engagement therewith.

On spindle N² is a sliding clutch-sleeve, U, longitudinally slotted at u to engage a pin, N³, on shaft N, which causes it to turn with said 10 shaft. This sleeve is also provided at its outer end with a lug, u², and at its inner end with a lug, u³, the former being for the purpose of engaging a pin, n⁵, on shaft N, and the latter for engaging a pin, n⁶, on spindle N². It is 15 not necessary to use both of these pins n⁵ n⁶. The one employed must be attached to the spindle N² to be practically operative, provided the pin N³ and slot n² connect the clutch-sleeve, as above described, to shaft N. 20 Of course they may connect it to spindle N² instead. A feather and groove or prismatic shape of shaft and sleeve interior may be substituted for this pin and slot. Shaft Q and spindle Q² are provided in like manner with 25 pins Q³ q⁵ q⁶, and united by a clutch-sleeve, U', having a slot, u', and terminal lugs u⁴ u⁵, these parts all being constructed, arranged, and operating as the corresponding ones on the other shaft. Clutch-sleeve U has an annular flange 30 or collar, U², and clutch-sleeve U' has a similar one, U³, a shifting-bar, V, which is fulcrumed at its middle, being slotted or recessed at each end to fit on said flanges. When said 35 bar is vibrated so as to shift one of said clutch-sleeves out of engagement, so that its roll will not be operated, it throws the other sleeve into engagement. Thus when the shaft N is 40 rotating the winding-roll to move the music-sheet for governing the playing of the instrument the shaft Q and the re-winding-roll are not in gear; but when the clutch-sleeve of the former shaft and roll is shifted out of gear the other clutch-sleeve, U', is simultaneously shifted into gear, so that the re-winding-roll 45 will be driven by the shaft Q. This latter shaft turns in the opposite direction from that of shaft N. The arrangement of the gearing is such as to make its motion more rapid. Thus the operation of rewinding is greatly 50 shortened.

The fan-shaft P is of course useless during the operation of rewinding, and to get it out of the way and lessen friction I employ an endwise-movable bar, V', which bears against 55 the inner end of said shaft and forces it outward, so as to remove the pinion p from engagement with the gear-wheel O' against the resistance of spring r. This bar is arranged to be struck and moved endwise by the shifting-lever when the latter puts the clutch-sleeve U' in position for the shaft Q to operate the re-winding-roll. When the pressure thereon is 60 removed, the spring r replaces the shaft P and endwise movable bar V' in their former position, so that the former will be in readiness for operating simultaneously with the winding-roll and acting as a fly-wheel therefor.

W designates the tracker-range over which the perforated music-sheet is drawn as it runs from the spool or re-winding-roll T to the winding-roll S. This tracker-range is disposed centrally of the action-board and wind-chest A', and extends down through the top or action board, A², and connects with the bottom board, X', the spool T and winding-roll S being located at right and left of the tracker-range, as indicated. The tracker is provided with the usual series of windways or ducts, w, at intervals corresponding with the lines of openings in the music-sheet, and said ducts w at the 80 lower edge of the tracker-range connect in alternate order with channels or windways w', formed in the bottom board, X', and extending right and left to positions beneath the sets of reeds, where they communicate with passages w², formed vertically through the bottom board.

Two separate sets of reeds, W', are employed, which are arranged in tube-blocks A³ upon the top of the wind-chest A', the air-passages a from the respective reed-cells passing down through the action-board A² in the usual manner of reed-board construction. The reed-valves W² are seated upon the under side of the action board for closing the 90 passages, and are confined in place by wire pins passing through slots in their ends, the valve being free to drop from its seat when unsupported by the actuating devices.

Ledges or bars y are arranged beneath the 100 ends of the valves W² to prevent either end thereof from falling too far away from their seats when released for opening.

A series of pneumatic motors, X, corresponding to the number of reed-valves W² and openings w², which latter are directly beneath the valves, are disposed beneath said openings and attached to the lower side of the bottom board, X', of the wind-chest, as illustrated. Said pneumatic motors are respectively connected 105 with the air-channels w' and with the wind-chest chamber by way of the passage w², and are collapsible by external air-pressure whenever partial vacuum is induced within them.

Pitman rods or pins W³ extend up from the 110 pneumatics X to the valves W² for operating them. Said pitmen pass through the openings w², their lower ends resting against the back of the valve in such manner that the collapse of the pneumatic will close the valve and expansion of the pneumatic will allow the valve to 115 open by its gravity and the air-pressure from above. The upper part of the pitman passes through a guide, G², or perforated strip fixed at a short distance below the valve, which 120 guide serves to keep the pitman end in proper relation to the valve; and also, if desired, acts as a stop for the downward movement of the valve. The only passage for inlet and outlet of air to or from the chamber of each pneumatic motor is through the space around the pitman or rod W³, which is made of a sectional area somewhat less than the area of the passage w², and any flow of air through said pas-

sage tends to carry the pitman in the direction of the flow or to assist the pitman in moving freely and quickly.

The operative action of the several pneumatic motors and reed-valves throughout the sets being similar, it will be sufficient to explain a single action, which is as follows: When the air in the wind-chest is exhausted by action of the main bellows and the tracker-duct 10 is closed by the music-sheet, the chamber in the pneumatic is exhausted through the passage w^2 to the wind-chest and the pressure of external air collapses the pneumatic motor and forces up the pitman W^2 , thereby holding the 15 valve W^2 closed so long as partial vacuum exists within the pneumatic motor. When the duct of the tracker is opened by a perforation of the music sheet passing over its mouth, the air passing in through said duct and the channel w' and down into the space around the pitman-pin equalizes the pressure externally and internally of the pneumatic motor, and the superior pressure then being on the valve W^2 and acting in the direction with the gravity of 20 the valve and pitman, effects the expansion of the pneumatic and allows the valve to fall, so as to open the passage for the flow of air through the reed, which thereupon sounds. When the unperforated part of the music- 25 sheet comes over the mouth of the air-duct and the inlet of air thereto is prevented, the exhaustion is again established within the wind-way and pneumatic X , which latter is immediately collapsed by external atmospheric 30 pressure, and by reason of its larger area overcoming the downward pressure on the valve, forcing upward the pitman and reed-valve and effecting the closure of the passage a to stop the sounding of the reed. Each reed-valve and 35 reed is operated in this manner according to the arrangement of the openings in the music-sheet and consecutively as the openings pass the tracker-range W .

The pneumatic and valve mechanism, constructed as herein shown, operates without the aid of springs for either opening or closing the pneumatic or valve, and is very simple, convenient, and practical for construction, and is not liable to derangement or to get out of order when handling or transporting the instruments.

Having thus described my invention, what I claim as new, and desire to secure by Letters Patent, is—

55 1. The combination, with the wind-chest and tracker-range in an automatic musical instrument, of a reed the air-passage for which is provided with a reed-valve seated upon the inner side of the top board of the wind-chest 60 and free to rise and fall, a pneumatic motor located externally upon the bottom of said wind-chest opposite said reed-valve, a wind-way leading from the tracker-range into said pneumatic motor, and also into the wind-chest, 65 and a pitman extending from the interior of said pneumatic motor to the back of said reed-

valve, and disposed within the passage or windway through which air is supplied to or exhausted from said pneumatic motor, substantially as set forth.

2. In an automatic musical instrument, the combination of an exhaust chamber or wind-chest having a series of openings through its bottom board, channels within said bottom board leading to said openings, a tracker-range 75 the ducts of which respectively communicate with said channels, a series of pneumatic motors disposed externally, and respectively covering the openings in said bottom, and a series of actuating pitmen or pins passing 80 through said openings from the interior of the wind-chest into the interior of the pneumatic motor for receiving motion therefrom, substantially as shown, whereby the entering and outgoing air is utilized to assist in the actuation 85 of said pitman, as set forth.

3. A wind-chest which has two series or sets of reeds on its upper side, two series of externally-disposed pneumatics on its under side, series of reed valves beneath said reeds, pitman-rods extending direct from said pneumatics to the respective reed-valves through passages in the bottom of the wind-chest, and a tracker-range the air-duets in which are alternately connected with channels extending 95 to the respective series of pneumatics, and a bellows mechanism for inducing exhaust-pressure within said wind-chest, substantially as set forth.

4. In an automatic musical instrument, a 100 tracker-range provided with a series of ducts or air-passages which connect alternately with two series of passages formed in the bottom board of the wind-chest and leading to series of pneumatic motors X , disposed on said bottom board at the right and left of said tracker, combined with a double series of reeds and reed-valves disposed upon the top of said wind-chest, and connections for operating said valves from the respective pneumatics, as set forth.

5. In an automatic musical instrument, the combination, as described, of a wind-chest the top and bottom boards of which are provided with air-passages, a series of reeds disposed 115 upon the exterior of the top board, a series of inwardly-opening reed-valves disposed on the interior of said top board, covering the air-passages opposite the respective reeds, a series of pneumatic motors disposed upon the 120 exterior of the bottom board and collapsible by external atmospheric pressure, a tracker-range having a series of air-duets connecting with passages leading into said pneumatic motors through the bottom board of the wind-chest, a perforated music-sheet acting as a valve for said tracker-duets, and pitman-pins connecting the respective pneumatics and reed-valves in their order for closing said valves when the pneumatic motor is collapsed 125 by reason of the exhaustive force upon the pneumatic being overcome by flow of air let 130

in through the tracker-duct as a perforation of the music-sheet passes over said duct, substantially as set forth.

6. The combination of a pedal, a driving-shaft, a ratchet-wheel on said shaft, a lever carrying a pawl which engages with said ratchet, a link connecting said pedal with said lever, and connections between said shaft and the bellows, substantially as set forth.

10 7. The combination of a pedal, a driving-shaft, a ratchet-wheel, a lever carrying a pawl which engages with said ratchet-wheel, a link connecting said pedal to said lever, a spring-drum wound by said shaft, a shaft 15 which is belted to said drum, and a winding-roll for the music-sheet, which is connected to the latter shaft, substantially as set forth.

8. In combination with the winding-roll and

rewinding-roll, two shafts respectively arranged to be clutched therewith, a shifting-lever and a pair of clutch-sleeves for effecting this clutching alternately, a sliding bar arranged to be operated by said lever when the winding-roll is unclutched, a fan-shaft normally in gear with the shaft which drives the winding-roll, but arranged to be thrown out by said bar, and a spring for replacing said fan-shaft in its normal position, substantially as set forth.

In testimony whereof I affix my signature in presence of two witnesses.

JOHN McTAMMANY.
